(57) CLAIM

The ornamental design for a hooking element for hanging
system with rail, as shown and described.

DESCRIPTION

FIG. 1 is a front perspective view of the hooking element of
the present invention; and,

FIG. 2 is a front view of the hooking element of the present
invention, wherein it is shown in engagement with a rail of a
hanging system.

The broken lines are for the purpose of illustrating environ-
ment and form no part of the claimed design.
